Primary Examiner — Austin Murphy(74) *Attorney, Agent, or Firm* — Berkeley Law & Technology Group, LLP(57) **CLAIM**

The ornamental design for a dish cloth holder, as shown and described.

DESCRIPTION

FIG. 1 is a top, left, and front perspective view of a dish cloth holder showing my new design;

FIG. 2 is a front elevational view of FIG. 1;

FIG. 3 is a rear elevational view thereof;

FIG. 4 is a right side elevational view of FIG. 1;

FIG. 5 is a left side elevational view of FIG. 1;

FIG. 6 is a top plan view of the dish cloth holder of FIG. 1;

FIG. 7 is a bottom plan view of the dish cloth holder of FIG. 1;

FIG. 8 is an isometric view of the dish cloth holder showing that the holder straddles a sink;

FIG. 9 is a schematic representation of a top view of the dish cloth holder hereof, illustrating a continuous, tubular/solid center rod of varying length; and,

FIG. 10 is a schematic representation of a front view of the dish cloth holder, illustrating a continuous, tubular/solid center rod of varying length.

The broken lines in FIG. 8 represent environmental subject matter and form no part of the claimed design.
